Baldwin Wright*

UNITED STATES PATENT OFFICE.

CHARLES H. KUGLER, OF LEXINGTON, NEBRASKA.

PLOWPOINT.

Application filed April 10, 1922. Serial No. 551,338.

To all whom it may concern:

Be it known that I, CHARLES H. KUGLER, a citizen of the United States, and resident of Lexington, in the county of Dawson and 5 State of Nebraska, have invented certain new and useful Improvements in Plow-points, of which the following is a specification.

My invention relates to a point for plows 10 that may be welded in place when the plow becomes worn and dull or the point is broken in any manner.

An object of my invention is to provide a point that will be simple in construction 15 but that will be efficient in use.

Another object is to provide such a point that may be readily welded in place by a blacksmith in a minimum of time and which will render the plow substantially as good 20 as new.

Other objects will be apparent from the following detailed description and the appended claims.

In the drawings:

Figure 1 is a perspective view of a plow share with a point welded in place as indicated.

Figures 2 and 3 are side views showing how the point may be applied to shares having their points worn to different shapes.

Figure 4 is a perspective view of the point itself.

The ordinary plow has a share A and a land side B forming an angle therewith, the 35 cutting edge of the share tapering off to a point of intersection with the landside. This point becomes worn quite rapidly in use becoming blunt, and is also not infrequently broken off. In either case the plow is rendered almost useless or in any event 40 its efficiency is reduced to a great extent. Unless some way is provided for replacing the point the whole share is rendered valueless and must be thrown away.

According to my invention an extra point is provided indicated as a whole in Figure 4 and designated by the reference letter C. This point C has one face 1 generally 50 triangular in shape that fits over the plow share, and a side 2 forming a part of the landside when the new point is applied. This part 2 is widest in the middle and tapers substantially to a point at each end as indicated at 3 and 4. These parts 1 and 2 may be made separately and welded

or drop forged together, or they may be made in a single piece.

The part 2 is provided with a lug 5 and the part 1 is provided with two lugs 6 and 7 at the upper and lower corners respectively.

Assuming that the point of the plow has been worn as indicated by the dotted line 8 in Figure 1 or as shown at 9 and 10 in Figures 2 and 3 respectively, a new point 60 C is slipped into position as shown in Figures 2 and 3. The ear or lug 5 fits on the inner side of the land side, the lug 6 fits over the outside of the landside at the top, and the lug 7 fits over the edge of the share. 70 These lugs serve to hold the device in position while it is being welded, and although they may be omitted in some cases, they add greatly to the value of the device.

After being placed in position the point 75 is welded to the front or cutting edge and landside portion of the share, the line of weld being indicated by the line 11 in Figure 1. The lug 5 is turned up on the inner side of the landside and welded thereto, the 80 lug 6 is turned down on the outer side of the land side at the top and welded thereto, while the lug 7 is turned over the front or cutting edge of the share and welded to the bottom thereof. After the new point is 85 welded in position the edge is sharpened in any desired manner, and the plow is substantially as good as new.

Since by far the greater part of the wear of the plow comes on the part that is thus 90 renewed, it is obvious that the life of the plow can be greatly lengthened by renewing the point as desired. The device is simple and cheap and can be applied by any blacksmith. Although I have described the preferred embodiment of my invention, it is 95 obvious that minor changes may be made without departing from the spirit thereof, and it is to be understood that the invention is limited only by the terms of the appended 100 claims.

I claim as my invention:

1. A plow point comprising a share portion substantially triangular in shape and having bent over lugs at its rear corners, 105 and a landside portion rigid therewith which tapers from the center toward each end and at its rear end has a bent over lug, the entire point being adapted to be welded on to a worn plow share. 110

2. A plow point comprising a share portion substantially triangular in shape and having bent over lugs at its rear corners, and a landside portion integral therewith which tapers from the center toward each end and at its rear end has a bent over lug, the entire point being adapted to be welded on to a worn plow share, in which operation the lug on the land side portion is 10 welded to the inside of the landside of the share, the top lug on the share portion is welded on the outside of the landside portion, and the bottom lug on the share portion is welded over the edge and on to the bottom of the front edge portion of the share.

3. A plow point comprising rigid share and landside portions which meet at the usual angle and are adapted to fit over a worn plow share, the share portion when welded to the share forming a continuation of the plow share and the landside portion forming a continuation of the landside portion of the plow, and lugs on the rear end of both the share and landside portions which are adapted to hold the point in position during the welding operation. 20 25

In testimony whereof, I have hereunto subscribed my name.

CHARLES H. KUGLER.
